CAN OPENER

Vineas Auge, Union Township,
Union County, N. J.

Application November 14, 1935, Serial No. 49,801

6 Claims. (Cl. 30—22)

This invention relates to can openers, an object of the invention being to provide a simple, efficient, strong and durable can opener which can be readily manipulated to cut the top or side 5 of a metal container, commonly known as a can, and which can be manufactured so cheaply as to provide each can with a can opener fragiley attached to the can so that it is in convenient position for removal and use.

10 A further object is to provide a can opener which will give a smooth cut and overcome the difficulties of ordinary can openers which leave a wavy cut endangering the operator's hands and preventing the removal of contents in bulk, such 15 as pressed meat or fish. My invention provides a device which is very compact, simple to manufacture, and lends itself advantageously to the general use required, either as a separate opener or it may be applied to a can of any shape, thus 20 providing handy means for opening.

Another object of this invention is to provide, in a device of this character, a reciprocating convex cutter in combination with cutter guides and cutter fulcra of novel and efficient action adapted 25 to automatically advancing and maintaining the cutting edge adjacent to the can seam.

30 A further object is the provision of means for insuring the advance of the cutter causing the device to be movable upon a plurality of fulcra by imparting to the device a rocking or oscillating movement during its cutting operation.

With these and other objects in view the invention consists in certain novel features of construction and combinations and arrangements of 35 parts, all of which will be more fully hereinafter described and pointed out in the claims.

In the accompanying drawings—

Fig. 1 is a view in elevation illustrating a preferred embodiment of my improved can opener; 40 Fig. 2 is a view in longitudinal section on the line 2—2 of Fig. 1;

Fig. 3 is a view in transverse section on the line 3—3 of Fig. 1;

Fig. 4 is a fragmentary view in elevation illustrating the initial position of the can opener on a can to begin the cutting operation;

Fig. 5 is a fragmentary view in vertical section on the line 5—5 of Fig. 4;

Fig. 6 is a view similar to Fig. 4, showing what 50 may be termed the completion of the first cycle of operation, that is, a complete movement of the upper end of the can opener to the left;

Fig. 7 is a fragmentary view in vertical section on the line 7—7 of Fig. 6;

55 Fig. 8 is a view similar to Figs. 4 and 6, illus-

trating what may be termed the second cycle of operation which is a movement of the upper end of the can opener partially to the right;

Fig. 9 is a view similar to Figs. 4, 6, and 8, showing what may be termed a completion of the 5 third cycle of operation which is a complete movement of the upper end of the can opener to the right;

Fig. 10 is a perspective view illustrating my improved can opener attached to an angular can; 10

Fig. 11 is a view similar to Fig. 10 illustrating a slightly modified form of can opener removably attached to a circular form of can;

Fig. 12 is a fragmentary view in vertical section showing the position of my improved can 15 opener when cutting the side of the can as distinguished from the top thereof;

Fig. 13 is a perspective view of a modified form of my can opener;

Fig. 14 is a fragmentary view in vertical section 20 illustrating the can opener shown in Fig. 13 in operative position to cut a can.

Referring more particularly to Figs. 1 to 9 inclusive of the drawings, 1 represents a bar or plate of metal which constitutes a blank and which throughout its lower portion is of some- 25

what the shape of a spear head or arrow head and which at its upper end is preferably provided with inturned portions 2 to afford a smooth and easy grip for the hand to manipulate the 30 device. The lower end of the bar or plate 1 is stamped or otherwise treated to provide a laterally offset blade 3, the line of attachment or point of offset of said blade being angularly disposed relevant to the longitudinal axis of the bar, as 35

shown at 4, and the remainder of the bar at its lower portion constitutes a blade guide 5. The blade has two curved and convex cutting edges 6 and 7 respectively, and adjacent the upper edges of these cutting edges 7 the bar or blank is provided with shoulders 8 and 9 respectively, which 40

constitute fulcra. The blade guide 5 is provided with an offset lug 10 which also constitutes a fulcrum, and this lug 10, as shown in most of the figures of the drawings, is offset from the inner edge of the blade guide in substantial parallelism with the cutting edge 6 and adjacent the sharp apex 11 of blade 3.

Furthermore it will be noted, particularly by reference to Fig. 3 of the drawings, that the blade 50 3 is disposed at an angle to the transverse plane of the blade guide, and it is of course to be noted that sufficient metal is removed between the cutting edges of the blade and the guide 5 to insure a proper operation of the tool.

Figs. 4 to 9 inclusive illustrate the several cycles or steps in the operation of cutting a can top, and the can is indicated by the reference character 12 and is provided with the ordinary seam 13 at its end. The initial position of the cutter is shown in Fig. 4 with the sharp apex 11 of the blade resting upon the upper end of the can adjacent the seam 13 and the lug 10 located under the seam at the outer portion of the can. The first step or 10 cycle is to utilize this lug 10 as a fulcrum under the seam 13 and swing the upper end of the device to the left, bringing the opener to the position shown in Fig. 6, and during this movement the blade will puncture the can top and cut through the same as indicated by the dotted lines in Fig. 6. The next cycle is to move the upper end of the can opener to the right, utilizing the shoulder 9 as a fulcrum and swinging the device to the position shown in Fig. 8. The next cycle is to complete 20 the swinging movement to the right, utilizing the shoulder 8 as a fulcrum, bringing the tool to the position shown in Fig. 9. These cycles are then repeated, of course advancing the blade as each complete set of cycles is ended.

25 As illustrated in Fig. 10 of the drawings, the can opener may be more or less fragilely connected to a can, and I have shown in Fig. 10 the can as of angular form, as it is obvious that the can opener may be used on an angular can as well as on a circular one. When in position on top of the can the lug 10 projects over the can seam and one corner of the handle portion of the blank may rest against the inner portion of the seam, and a spot weld, drop of solder, or any other 30 securing device may be employed to temporarily hold the can opener in place.

Fig. 11 illustrates my improved can opener connected to and supported upon a circular can, and in this view I illustrate a slight modification in 35 that the lug 14 corresponding to lug 10 of the preferred form is at the outer edge of the guide 5 instead of at the inner edge, and an additional lug 15 extends from the edge of the device, and both of these lugs are positioned over the seam 40 of the can.

Fig. 12 illustrates the fact that my improved can opener may be utilized to cut the side wall of the can and shows the position of the can opener in performing this function.

45 Figs. 13 and 14 illustrate a modified form of can opener in which the bar or blank 1 is provided with an integral transversely extending bar 16 having oppositely curved ends 17 and 18 to afford thumb and finger holds in the manipulation of the device. In other respects the can opener is constructed like that above described and operates in the same manner except of course that the bar 16 in the modification is grasped instead of the upper end of the bar or blank.

50 It will be noted that the fulcrum lug 10 has sharp corners and as this fulcrum lug lies close against the surface of the can it will scratch the can body or mutilate the label on the can body, as indicated at 19 in Fig. 9 of the drawings. This 55 automatically mutilates the surface of the can body when the can is opened. Such defacement is particularly desirable on lithographed cans as

more expensive products are packed in decorated cans and are subject to illegal use and refilling.

While I have illustrated several modifications of my invention and pointed out in detail the preferred embodiments thereof, it is to be distinctly understood that I do not wish to limit myself at liberty to make such changes and alterations as fairly fall within the spirit and scope of the appended claims.

10 I claim:

1. A can opener, including a blade guide, a blade laterally offset therefrom and a fulcrum lug offset laterally from the blade guide and located at a point adjacent the apex of the blade, 15 said blade guide having shoulders adjacent the upper extremities of the cutting edges of the blade which also constitute fulcrums.

2. A can opener comprising a blank, a blade laterally offset from said blank and having convexly curved cutting edges and a sharp apex at 20 its lower end, and a blade guide in juxtaposition to the edges of the blade and having three fulcrum points, one adjacent the apex of the blade and the others adjacent the upper extremities 25 of the cutting edges of the blade.

3. A can opener comprising a blank, a blade laterally offset from said blank and having convexly curved cutting edges and a sharp apex at 30 its lower end, and a blade guide in juxtaposition to the edges of the blade and having three fulcrum points, one adjacent the apex of the blade and the others adjacent the upper extremities 35 of the cutting edges of the blade, said blade offset from the blank at an angle to the longitudinal axis of the blank.

4. A can opener comprising a blank, a blade laterally offset from said blank and having convexly curved cutting edges and a sharp apex at 40 its lower end, and a blade guide in juxtaposition to the edges of the blade and having three fulcrum points, one adjacent the apex of the blade and the others adjacent the upper extremities 45 of the cutting edges of the blade, and a hand-gripping bar at right angles to and integral with one end of the blank.

5. A can opener, including a blade guide, a blade laterally offset therefrom, and a fulcrum lug offset laterally from the blade guide and located at a point adjacent the apex of the blade, 50 said fulcrum lug being relatively sharp and adapted when the can opener is operated to cut through one wall of the can body to deface the surface of another wall of the can body.

6. A can opener comprising a blank having a handle thereon, said blank being of general spear-head shape and of sheet metal, a blade cut out of the body of the blank and laterally offset therefrom and of the same general spear-head shape as the blank, said blade having sharpened edges, a laterally offset lug at the inner edge of the blank adjacent the apex of the blade and constituting a fulcrum to engage under the seam of a can, and said blank having two fulcrum points at opposite sides and at the upper end of 60 the blade.

65 VINCAS AUGE.
